UNITED STATES PATENT OFFICE

CHARLES S. BURTON, OF OAK PARK, ILLINOIS

VACUUM-OPERATED PUMPING DEVICE

Application filed June 2, 1928. Serial No. 282,453.

The purpose of this invention is to provide an improved construction of a pumping device suitable for lifting liquid from a low level source for supplying a receptacle at a higher level from which it may flow by gravity to the place of consumption, as for example, the carburetor of an internal combustion engine, the liquid lifted being fuel for the engine. More specifically the purpose is to accomplish such lifting or pumping by means of suction, of which the source in the case of a device employed for supplying fuel to an internal combustion engine will be the intake manifold of the engine. And in such case the invention has the more specific purpose of making it possible to dispense with any valve control of the suction connection. The invention for these general and specific purposes consists in the elements and features of construction shown and described as indicated in the claims.

In the drawings:

Figure 1 is a vertical section of a vacuum fuel feeding device embodying this invention.

Figure 2 is a section at the line 2-2 on Figure 1.

Figure 3 is a perspective view of a valve device which is characteristic of the invention.

The construction shown in the drawings consists of the reservoir or liquid accumulating chamber, A, within which there is suspended at the upper part a liquid receiving chamber, hereinafter called the liquid receptacle, B, these two chambered members being secured together at their upper ends and the liquid receptacle, B, being closed at the top, by a cap plate, C, which is provided with a suction port, 20, arranged for pipe connection with a source of suction, as the intake manifold of the engine served, and a fuel inlet port 30 arranged for pipe connection with a source of liquid to be lifted, as liquid fuel for supplying the engine. The cap plate, C, affords means also for a valve-controlled atmosphere inlet port; and for economy of construction and convenience of assembling, the cap plate comprises a separable relatively thin plate member, 50, which is

mounted on the top of the cast member, C, of the cap plate, closing a circular aperture, c, in the latter, and being secured to said cast member by screws, 54, with an intervening gasket, 55, for making the joint between the two parts of the cap plate substantially air tight. The plate, 50, has a slit, 51, which constitutes the atmosphere inlet port; and this port is controlled by a valve member, 60, hereinafter more particularly described. The receptacle, C, has at the bottom a liquid outlet through an angle or elbow fitting, 40, whose discharge aperture, 41, is controlled by an exteriorly applied valve, 42, adapted to be opened by liquid outflow from the receptacle and normally seated by gravity and adapted to be held seated against liquid outflow by suction when the receptacle is in the condition of partial vacuum or sub-atmospheric pressure, which condition it will be understood will result from open suction connection of the receptacle with the source of suction.

A float, 70, in the receptacle is guided on a rod, 80, which at its upper end has lost motion connection by a pivot terminal, as seen at 81, with the valve, 60, by means of a slotted lug, 61, which projects from the under side of the valve through the slit, 51, which constitutes the atmosphere inlet port; and the rod, 80, has a finger, 82, which juts off from it at a short distance below the pivot terminal, 81, which engages the slot of the lug, 61, said finger, 82, projecting through the slit, 51, at the extreme narrow end of the latter, for encounter with the end portion of the valve, 60. The purpose of this particular construction will be hereinafter explained.

At the lower end of the rod, 80, which extends down through the float, 70, which has a vertical aperture, 71, for that purpose, the rod protrudes through an eye 72^a in a lug, 72, which is secured on the under side of the float, projecting under the vertical aperture, 71, of the latter; and the rod has a stop, 83, below said eye, and a second stop, 84, a certain distance above the eye; by this means the float is adapted to move vertically along the rod for the distance which separates the two stops, 83 and 84.

The slit, 51, constituting the atmosphere inlet is desirably tapered in width from very narrow dimension at one end to several times the dimension at the other end; and in forming the slit, the marginal portion is struck up from the plate, 50, to form by the upper edge of said upstruck margin, the seat for the valve, 60, which is tapered correspondingly to the taper of the slit. This valve member, 60, at least as to its narrower end portion, is made of quite thin and of very resiliently flexible metal as watch spring steel; but for convenience of mounting it, its pivoted end portion is a sheet metal stamping, 60^a, which is formed from a blank, as may be understood from Figure 3, folded to afford a short attaching portion, 60^m, for the spring portion, 60, of the valve, at a slightly acute angle to an upstanding arm, 60^p, carrying at its upper end a weight 64, and is formed with lug portions, 60^u, 60^u, which are folded up at right angles to the portion, 60^m, for receiving a pivot pin, 63, which is inserted through the side walls of a housing or hood, 90, which is a sheet metal stamping of simple rectangular form dimensioned for enclosing the valve with freedom of movement for opening and closing, said hood being perforated for freely admitting atmosphere while it serves also to screen the valve and its seat from dust and larger floating particles which might obstruct the seating of the valve. This hood is secured in place on the plate, 50, by screws, 91, taken through lugs, 90^a, folded out from the side walls of the hood.

The operation of the structure described may be understood to be as follows:

The receptacle being connected at 30 by pipe leading from a source of liquid, and at 20 by a pipe leading from a source of suction, a condition of partial vacuum or sub-atmospheric pressure is developed in the receptacle, B, causing liquid to be lifted from the liquid source and discharged into the receptacle, B, eventually filling the receptacle to a depth at which the float, 70, will be upheld at a position shown in dotted line in Figure 1, bringing the eye, 72^a, on the float up against the upper stop, 84, on the rod, 80, and lifting the rod until the finger, 82, is in contact with the under side of the spring valve, 60, at the narrower thin end of the latter, where said narrow end is exposed at the narrow right hand end portion of the slot, 51, which constitutes the atmosphere port. The spring valve, it will be understood, is now held forcibly on its seat by the excess of atmosphere pressure at the outer side over the reduced pressure in the receptacle; and this excess pressure operating on the relatively large area of the spring valve, tends to exceed the buoyant value of the float, even when the latter is fully submerged, as it will become if the atmosphere

valve is not opened so as to admit atmosphere to the receptacle. But though this pressure over the large area of the valve may exceed the buoyancy of the submerged float, the latter will be sufficient to upwardly flex the thin narrow resiliently flexible right hand end portion of the spring valve, as seen in dotted line at 60^a in Figure 1; and thereby atmospheric pressure is admitted to the receptacle, reducing the suction hold on the valve; and at some point early in the buoyant upward action of the float, the flexure of said end portion of the spring valve, 60, will have opened the atmosphere port far enough to reduce the suction hold; and the resiliency of the spring valve coming into action for straightening the valve, said valve will snap up and straighten, as seen in dotted line at 60^b in Figure 1; and in doing so, it will cause the upright arm, 60^p, to carry its weighted upper end over past the vertical plane of the pivot, to a position at which it will overbalance the valve and cause the latter to swing up to the limit permitted by the length of the slot of the lug, 61, or to the top of the hood whichever distance is greater; and thus the atmosphere port will be fully opened admitting air to the receptacle so far in excess of the amount withdrawn by the suction that the liquid which has been lifted by the suction and upheld from outflow past the valve, 42, by the vacuum developed in the receptacle while the atmosphere valve was closed, will no longer be upheld, but will flow out by gravity through the outlet port, 41, until the depth of liquid in the receptacle is only that which can be upheld by the low degree of vacuum resulting from the suction operating through the suction port, 20, which is very small in comparison with the size of the full open atmosphere port, the latter being many times larger than said suction port.

In practice the atmosphere port, 51, and the total effective area of the atmosphere valve, 60, may be very easily made fifty to one hundred times the effective area of the suction port; and the extent of the narrow end portion of the valve which will be flexed up by the buoyant effort of the float is sufficient to open enough of the atmosphere port to reduce the vacuum to a degree at which the resilient reaction of the spring valve, 60, will cause the latter to snap straight and open the entire area of the atmosphere port.

When the vacuum is thus broken, permitting the liquid to discharge, as described, the lowering of the float lowers the rod, 80, until the pivot terminal, 81, reaches the end of the slot in the lug, 61, and the rod then hangs suspended from the lug, the weight, 64, at the upper end of the arm, 60^p, of the valve member, 60^a, being made heavy enough to uphold the rod, 80, while the liquid level continues to fall and the float continues to descend until the eye, 72^a, encounters the lower

stop, 83, on the rod and pulls the valve, rocking its weighted arm back past the vertical position so that the valve is lowered to its seat and held seated by gravity and the residue due of suction in the receptacle. And the continuing suction thus builds up the vacuum as before, and causes the receptacle to be refilled with liquid, and the cycle of the action, as described, is then repeated.

10 I claim:

1. In a construction for the purpose indicated, in combination with a receptacle for liquid having connections for receiving liquid from a liquid source and connections with a source of suction, and having an atmosphere inlet port, a valve for controlling said port, an outlet for the liquid and a valve controlling said outlet arranged to open in the direction for outflow and adapted to be seated by suction, a float in the chamber and a rod extending therefrom for actuating the atmosphere controlling valve, the atmosphere port being a relatively long narrow slit in the chamber wall, the valve for controlling it being a light flat flexibly resilient strip lodged at the outer side of the slit and seating on the margin thereof, and means retaining the valve against edgewise displacement from said seat, the rod having a terminal protruding through the slot at one extremity of the latter for encounter with the resilient valve strip at the corresponding end portion of the latter, said valve strip at that end portion being sufficiently flexible to be flexed away from its lodgement on the margin of the slit for a relatively short portion of the length of the latter, while the remainder of the length is held to the seat by the atmosphere pressure.

2. In the construction defined in claim 1, the valve strip being pivoted at the end remote from that at which the float-actuated means encounters it, and said member having a lost motion connection with the valve at the under side at a point intermediate its pivot and the point of said encounter.

3. In the construction defined in claim 1, the valve strip being pivoted at the end remote from that at which it is encountered for flexing it for opening, and having a weighted arm extending upwardly from its pivot in direction to be over-weighted toward the encountered end of the valve at seated position of the latter, and to be over-weighted in the opposite direction at the opened and straightened position of the valve.

4. In the construction defined in claim 1, the float being mounted for sliding up and down on the valve-actuating rod and said rod having stops which limit said up and down movement of the float, the rod having a lost motion connection with the valve arranged for such last motion in the up and down movement of the rod.

5. In the construction defined in claim 1, the float being mounted for sliding up and

down on the valve-actuating rod and said rod having stops which limit said up and down movement of the float, the rod having a lost motion connection with the valve arranged for such lost motion in the up and down movement of the rod, the valve being adapted for holding itself at open position by gravity and at said position supporting the rod.

In testimony whereof, I have hereunto set my hand at Chicago, Illinois, this 29th day of May, 1928.

CHARLES S. BURTON.
